UNITED STATES PATENT OFFICE

JAMES S. THOMPSON, OF NEW ROCHELLE, NEW YORK, ASSIGNOR TO FIREBAR CORPORATION, OF CLEVELAND, OHIO, A CORPORATION OF DELAWARE

GRATE

Application filed August 19, 1930. Serial No. 476,262.

This invention relates to grate bars of the type used for heavy duty purposes, such as in locomotives, boiler furnaces, and the like, and is concerned more particularly with a grate bar which includes a longitudinal member or carrier and a plurality of fuel-supporting units extending beyond the lateral edges thereof. These units may be formed integrally with the carrier but are preferably mounted loosely thereon and have a limited freedom of angular movement relative to the carrier.

In the co-pending application of Buckley, Serial No. 338,352, filed February 8, 1929, there is described and claimed a grate bar of the general description above given and, as commonly constructed, this grate bar is made entirely of cast metal. While this bar has proven highly satisfactory in operation under severe conditions, it sometimes happens that the units become fractured during service, in which event the two parts of the unit fall free of the carrier bar, leaving an opening in the grate surface.

The present invention is accordingly directed to the provision of a grate bar of the type described in which the units are reinforced by simple inexpensive means so that in the event of a fracture the two parts of the unit are held together and the unit may be retained in service indefinitely.

For a better understanding of the invention, reference may be had to the accompanying drawing, in which

Fig. 1 is a cross-sectional view of a grate bar constructed in accordance with the invention and showing one of the fuel-supporting units in side elevation;

Figs. 2 and 3 are sectional views on the lines 2-2 and 3-3, respectively;

Fig. 4 is a fragmentary side elevational view of a grate bar of the invention; and

Fig. 5 is a plan view of a single unit.

Referring now to the drawing, the grate bar in one form comprises a carrier which may include a horizontal web 10 provided with a strengthening rib 11 along its under surface and having a downwardly extending shaker arm 12 at an appropriate point. At the ends of the carrier are upstanding arms

13 provided with supporting means 14 which may take the form of trunnions when the bar is to be mounted in a grate frame. Extending upwardly from the top of the web is a centering flange 15 having a rounded top.

Mounted on the carrier between the arms is a plurality of fuel-supporting units, each of which consists of a plate 16 from one or both faces of which projects a row of spaced lugs 17, these lugs defining vertical air passages 18 for upward flow of air to the fuel bed. At its top, each lug terminates in fuel-supporting projections 19 and preferably these projections are arranged in groups of four, two projections of each group lying above the top of a lug while the other two lie above the top of the plate adjacent to the lug. The projections of each group are separated by intersecting air channels 20 and 21, the latter communicating with the passages 18 between lugs 17. The projections have flat fuel-supporting tops and as these tops are of small area, excellent combustion is obtained by reason of the wide distribution of air to the fuel which takes place. Preferably the pair of lugs at the middle of the row are made solid as indicated at 22 to strengthen the unit at that point.

On the lower edge of the plate there is a recess 23 having a shape generally similar to the cross-sectional shape of the carrier and near the open end of the recess the plate is provided with locking projections or lugs 24. In the rocking of the grate bar, the units have a limited degree of angular movement relative to the carrier and one or the other of the locking lugs moves into engagement with the under surface of the web 10 to limit the relative movement and lock the units to the carrier.

Each unit is provided with one or more strengthening or reinforcing members 25 incorporated therein in the casting of the unit. These reinforcing elements lie wholly within the outline of the unit and the shape of each element is preferably closely similar to the shape of the unit. The reinforcing material which I prefer to employ is a sheet having a plurality of openings or perforations therein,

one or more of such sheets lying embedded in the body of the plate 16 with the metal of the plate passing through the openings and anchoring the sheets in position. A reinforcing element of metal network such as expanded metal is satisfactory for the purpose, and preferably there are a plurality of reinforcing sheets within each unit. In the formation of the unit, the sheets cut to proper form are inserted in the mold in proper position and when the molten metal is poured into the mold, it flows through and around the sheets so that they become wholly embedded within the unit.

15 In the case of ordinary cast units, when cracking occurs in service, the fracture most frequently extends across the narrowest part of the unit near its mid-point. With the new unit including the reinforcing material, such fractures are largely prevented, but if one occurred, it would not result in the two parts of the unit falling from the carrier-bar since the reinforcing material is not subject to cracking and would maintain the unit in its original condition. In a fractured unit, the reinforcing material is subjected to tension under the load of fuel carried by the unit but sheets of relatively light foraminous or reticulated material provide sufficient strength to keep the parts of the unit together and it may be continued in service for a considerable period before being replaced.

What I claim:

35 1. A grate bar which comprises a longitudinal member and cross-bars mounted removably thereon and extending beyond the lateral edges thereof, each cross-bar including a plate having spaced lugs projecting from at least one face thereof and extending 40 downward from the top of the plate and a reticulated reinforcing element embedded within said plate, said element having substantially the same shape and area as said plate.

45 2. A grate bar which comprises a longitudinal member and cross-bars mounted removably thereon and extending beyond the lateral edges thereof, each cross-bar comprising a plate of cast metal supported on edge by said member, said plate having a sheet of expanded metal embedded therein, said sheet having substantially the same shape and area as said plate.

55 3. In a grate bar, a fuel-supporting unit of cast metal and a reinforcing element of expanded metal embedded in said unit and having a shape and area substantially the same as that of the unit, said element extending 60 substantially to the boundaries of said unit.

4. In a grate bar, a fuel-supporting unit comprising a plate having a row of spaced lugs projecting outwardly along at least one face, and extending vertically downward 65 from the top thereof, and a reinforcing ele-

ment within the plate extending beyond the lower ends of said lugs.

5. A grate bar which comprises a longitudinal supporting member, and a plurality of cross-bars mounted thereon, each cross-bar having an upwardly extending recess in its lower edge in which said member is received and being made up of a plate-like body of cast metal with a reinforcing element embedded therein, said element having a shape and area substantially the same as that of said body.

In testimony whereof I affix my signature.

JAMES S. THOMPSON.
